UNITED STATES PATENT OFFICE.

JAY B. RHODES, OF KALAMAZOO, MICHIGAN, ASSIGNOR TO WESTERN WHEELED SCRAPER COMPANY, OF AURORA, ILLINOIS, A CORPORATION OF ILLINOIS.

DUMP-CAR.

1,245,382.

Specification of Letters Patent. Patented Nov. 6, 1917.

Application filed August 18, 1916. Serial No. 115,691.

To all whom it may concern:

Be it known that I, JAY B. RHODES, a citizen of the United States, and a resident of Kalamazoo, in the county of Kalamazoo and State of Michigan, have invented certain new and useful Improvements in Dump-Cars, of which the following is a specification, reference being had to the accompanying drawings.

10 My invention relates to dump-car of the general type shown in my application for Letters Patent, Serial No. 98,495, filed May 19, 1916, and particularly to the mechanism for controlling the operation of the plungers 15 by which the body of the car is dumped toward one side or the other and thereafter brought back to its normal horizontal position. It is the principal object of my invention to provide a form and arrangement 20 of parts by reason of which when the car-body is to be righted toward the side of the car at which the cylinder is located by which the dumping of the car was effected, an exhaust port from such cylinder is automatically opened when the pressure from the train-pipe has been relieved, permitting the plunger to descend by its own weight. It is another object of my invention to improve devices of this type in sundry details 25 whereby the righting of the car-body may be effected properly and easily regardless of the amount of pressure which may have been required for dumping the car. The preferred means by which I have accomplished my objects are illustrated in the accompanying drawings and are hereinafter specifically described. That which I believe to be new and desire to cover by this application is set forth in the claims.

40 In the drawings,—

Figure 1 is a fragmentary view, being a transverse section taken across the car near one end thereof;

Fig. 2 is an enlarged detail, being a transverse sectional view through the exhaust valve;

Fig. 3 is an enlarged detail, being a transverse sectional view through the stop-and-waste cock by which the pressure from the 50 train-pipe may be removed from a single cylinder independently of the remaining cylinders.

Referring to the several figures of the drawings, in which corresponding parts are indicated by the same reference characters,

10—11 indicate longitudinally-extending I-beams comprising a portion of the main framework of a car. Pedestals 12 of any suitable type are mounted upon the I-beams 10—11 having pivotally connected therewith 60 brackets 13 by which the body 14 of the car is pivotally mounted so as to be adapted to be tipped in either direction, as desired, for dumping the load. Transversely-extending beams 15 support cylinders 16—17 provided with plungers 18—19, respectively, which are adapted to be raised relative to the cylinders by steam or other suitable fluid under pressure introduced through the train-pipes 20—21. Plunger-rods 22 are pivotally connected with the plungers 18—19 at their lower ends and at their upper ends are pivotally connected with transversely-extending links 23 which in turn are pivotally mounted upon brackets 24 rising from 70 the I-beams 10—11. 25—26 indicate the members of thrust-bars which are pivotally connected at their upper ends with blocks 27 carried by the bed 14, the lower ends of the thrust-bars being pivotally connected 80 with the brackets 24 by means of links 28. The links 23 are provided with hooked arms 29, pivotally mounted thereon, adapted to engage at their lower ends the outer ends of arms 30 which are mounted upon rock-shafts 31 which form a portion of the means for locking the car-body in normal horizontal position. Inasmuch as the parts so far described are all of the type shown and described in my application Serial No. 90 98,495 above referred to, it is not believed to be necessary to describe further their construction or operation.

Referring particularly to Fig. 2, 32 indicates a valve casing adapted to be connected 95 between the train-pipe and the piston, it being understood that each piston is provided with a valve of this type. This valve comprises a rotary valve stem or plug 33 interposed between an inlet chamber 34 and 100 an outlet chamber 35, said plug being provided with a port 36 extending therethrough, which is adapted to be closed by a proper rotation of the plug 33 in either direction from the position shown in Fig. 2. The 105 inlet chamber 34 is provided with a sleeve 37 provided with openings 38 in its side through which the steam or other fluid under pressure must pass. Other means is provided for closing the inlet chamber 34, 110

comprising a head 39 movable longitudinally of the sleeve 37 so as to cover the inner ends of the openings 38 of said sleeve. The head 39 is normally held by a spring 40 in raised position so as to close the openings 38, said spring 40 being adapted to act upon the head 39 through the medium of a stem 41 suitably connected therewith. The outlet chamber 35 is provided with an exhaust 10 port 42 leading therefrom, such exhaust port 42 being adapted to be closed by a washer or gasket 43 mounted on the lower end of the stem 41 when such stem is held in its lowermost position against the action of the 15 spring 40. The plug 33 extends outward through the wall of the casing 32, being provided at its outer end with a crank-arm 44 which is pivotally connected by means of a link 45 with the link 23 at that side of 20 the car, the connection of the link 45 with the arm 44 involving a slot 45^a adapted to permit the link 45 to move downward relative to the pivot pin 49 without affecting the position of the arm.

25 46 indicates a stop-and-waste cock interposed between the valve 32 and the train-pipe. As best shown in Fig. 3, this cock comprises a rotary plug 47 provided with a port 48 extending therethrough and a port 30 49 communicating with the port 48 and extending at right angles therefrom. When the plug 47 is in the position shown in Fig. 3, free communication is afforded between the train-pipe and the valve 32, but when the 35 plug 47 is given a quarter turn in counterclockwise direction in Fig. 3 by means of the handle 50 mounted upon said plug 47, it will be understood that the communication between the train-pipe and the valve 40 32 will be cut off and that the inlet side of the valve 32 will be opened to the atmosphere through the ports 49 and 48. It will be understood that when all the cars of a train are to be dumped simultaneously, the 45 valves 46 will all be maintained in the condition shown in Fig. 3, the entire dumping operation being then controlled by the engineer at the locomotive. When, however, it is desired that all the cars of a train be 50 dumped at the same point, rendering it necessary to dump one car at a time, the plugs 47 of all the valves 46 will prior to the dumping operation be given a quarter turn from the position shown in Fig. 3 so as to 55 shut off communication between the train-pipe and each of the valves 32. The dumping of each car is then controlled by the manipulation of the valve 46 of that car independently of the remaining cars of the 60 train.

With the valves 46 of the several cars of a train in the position shown in Fig. 3, with the stems 41 of the valves 32 in their uppermost positions closing the openings 38 of the 65 sleeves 37, and with the car-bodies 14 all in

normal horizontal position, when it is desired to dump the several cars simultaneously, the engineer admits steam or other fluid under pressure into the train-pipe 20 or 21 for operation of the plunger at that side of the car for dumping the car toward the opposite side. The fluid under pressure, passing through the valve 46, comes in contact with the upper face of the head 39, forcing the stem 41 downward against the action of the spring 40, serving to uncover the openings 38 and to close the exhaust port 42. The fluid under pressure is thus admitted to the lower end of the cylinder 16 or 17, serving to force the plunger upward for dumping the car as described in my prior application Serial No. 98,495 above referred to. As the plunger moves upward, the link 45 is carried upward by reason of its connection with the link 23, serving to turn the plug 33 of the valve 32 in counterclockwise direction in Fig. 2. The connections and proportions are such that the plug 33 serves to cut off the supply of fluid under pressure from the cylinder approximately 90 when the plunger reaches its uppermost position. When thereafter the pressure at the upper ends of the valves 32 is relieved by the manipulation of a proper valve at the locomotive, the pressure upon the upper faces of the heads 39 is relieved, permitting the springs 40 to move the stems 41 upward, serving to close the openings 38 and to open the exhaust ports 42. The plungers of the several cars are then free to descend by their own weight, forcing the steam or other fluid under pressure out of the cylinders through the exhaust ports 42. In this movement, the links 45 move downward relative to the arms 44 until the upper ends 95 of the slots 45^a engage the pins 45^b, whereupon the plugs 33 of the valves 32 are again moved to normal position, ready for a subsequent dumping operation. If it is desired to have the plunger of a single car 100 lowered for permitting the righting of that car separately, this would be effected through the manipulation of the valve 46 of that car serving to relieve the pressure at the upper end of a single valve 32 independently of 105 the train-pipe.

It will be understood that when the cars are to be dumped separately, the pressure in the train-pipes 20-21 will be maintained constant. The fluid under pressure will then be admitted for the dumping operation through a proper manipulation of the plug 47 of the valve 46, and the pressure will be relieved in due time by the proper reverse movement of the handle 50 of the valve 46 110 so as to permit the spring 40 to act to open the exhaust port 42.

When in the course of the downward movement of one of the plungers by its own weight the plug 33 is rotated sufficiently 115

to open communication between the outlet chamber 35 and the inlet chamber 34 through the medium of the slotted link 45, the pressure of the fluid in the cylinder will always 5 have been entirely relieved through the exhaust port 42.

By the use of my improved mechanism the plunger of each car is adapted to descend by its own weight for exhausting the 10 cylinder regardless of the pressure which was required in the cylinder for dumping the car, the exhaust port from the cylinder being opened by the valve spring regardless of the amount of pressure in the cylinder. 15 The plungers are thus insured against being forced down in unexhausted cylinders, whereby there is no danger at any time that any of the parts shall be broken by the operation of righting the car-body.

20 That which I claim as my invention, and desire to secure by Letters Patent, is,—

1. In a dump-car, the combination of a cylinder, a plunger therein, means for feeding fluid under pressure to said cylinder, 25 means actuated by said plunger for dumping said car, means comprising a valve actuated by a dumping operation for shutting off the supply of fluid under pressure from said cylinder, and means automatically effective when the pressure is relieved at the 30 inlet end of said valve to open an exhaust port from said cylinder for permitting the plunger to descend by its own weight.

2. In a dump-car, the combination of a 35 cylinder, a plunger therein, means for feeding fluid under pressure to said cylinder, means actuated by said plunger for dumping said car, means actuated by a dumping operation for shutting off the supply of fluid 40 under pressure from said cylinder, and yielding means adapted to open an exhaust port from said cylinder for permitting the plunger to descend by its own weight.

3. In a dump-car, the combination of a 45 cylinder, a plunger therein, means for feeding fluid under pressure to said cylinder, means actuated by said plunger for dumping said car, means comprising a valve actuated by a dumping operation for shutting off the supply of fluid under pressure from 50 said cylinder, and yielding means effective when the pressure is relieved at the inlet end of said valve to open an exhaust port from said cylinder for permitting the plunger to descend by its own weight.

4. In a dump-car, the combination of a cylinder, a plunger therein, means for feeding fluid under pressure to said cylinder, 55 means actuated by said plunger for dumping said car, and a valve comprising an inlet chamber, an outlet chamber, means actuated by a dumping operation for closing communication through said valve from said inlet chamber to said outlet chamber, an exhaust 60 port leading from said outlet chamber, and a valve 65

means controlled by the pressure at the inlet end of said valve for closing said exhaust port.

5. In a dump-car, the combination of a cylinder, a plunger therein, means for feeding fluid under pressure to said cylinder, 70 means actuated by said plunger for dumping said car, a valve,—comprising an inlet chamber, an outlet chamber, means actuated by a dumping operation for closing communication through said valve from said inlet chamber to said outlet chamber, an exhaust port leading from said outlet chamber, and spring-seated means actuated by the pressure at the inlet end of said valve for closing 80 said exhaust port against the action of said spring,—and means for relieving the pressure at the inlet end of said valve.

6. In a dump-car, the combination of a cylinder, a plunger therein, means for feeding fluid under pressure to said cylinder, 85 means actuated by said plunger for dumping said car, and a valve comprising an inlet chamber, an outlet chamber, means actuated by a dumping operation for closing 90 communication through said valve from said inlet chamber to said outlet chamber, an exhaust port leading from said outlet chamber, and a spring-seated head extending from said inlet chamber to said outlet chamber 95 and adapted to be moved against the action of said spring for closing said exhaust port.

7. In a dump-car, the combination of a cylinder, a plunger therein, means for feeding fluid under pressure to said cylinder, 100 means actuated by said plunger for dumping said car, and a valve comprising an inlet chamber, an outlet chamber, means actuated by a dumping operation for closing 105 communication through said valve from said inlet chamber to said outlet chamber, an exhaust port leading from said outlet chamber, a perforated sleeve in said inlet chamber, and a spring-seated head slidably mounted in said sleeve adapted to be moved by said spring into position in said sleeve 110 to close its perforations and adapted to be moved by the pressure at the inlet end of said valve against the action of said spring for opening said perforations and for closing 115 said exhaust port.

8. In a dump-car, the combination of a cylinder, a plunger therein, means for feeding fluid under pressure to said cylinder, 120 means actuated by said plunger for dumping said car, and a valve comprising an inlet chamber, an outlet chamber, means actuated by a dumping operation for closing communication through said valve from said inlet chamber to said outlet chamber, an exhaust 125 port leading from said outlet chamber, a perforated sleeve through the openings in which the fluid under pressure is admitted to said inlet chamber, and a spring-seated head slidably mounted in said sleeve adapt- 130

ed to be moved by said spring into position in said sleeve to close its perforations and adapted to be moved against the action of said spring by fluid under pressure at the 5 inlet end of the valve for opening said perforations and at the same time closing said exhaust port.

9. In a dump-car, the combination of a cylinder, a plunger therein, means for feeding fluid under pressure to said cylinder, means actuated by said plunger for dumping said car, a valve,—comprising an inlet chamber, an outlet chamber, means actuated by a dumping operation for closing communication through said valve from said inlet chamber to said outlet chamber, an exhaust port leading from said outlet chamber, a perforated sleeve through the openings in which the fluid under pressure is admitted to said inlet chamber, and a spring-seated head slidably mounted in said sleeve adapted to be moved by said spring into position in said sleeve to close its perforations and adapted to be moved against the 15 action of said spring by the fluid under pressure at the inlet end of the valve for opening said perforations and at the same time closing said exhaust port,—and means for

relieving the pressure at the inlet end of said valve.

10. In a dump-car, the combination of a cylinder, a plunger therein, means for feeding fluid under pressure to said cylinder, means actuated by said plunger for dumping said car, a valve,—comprising an inlet chamber, an outlet chamber, means actuated by a dumping operation for closing communication through said valve from said inlet chamber to said outlet chamber, an exhaust port leading from said outlet chamber, a perforated sleeve through the openings in which the fluid under pressure is admitted to said inlet chamber, and a spring-seated head slidably mounted in said sleeve adapted to be moved by said spring into position in said sleeve to close its perforations and adapted to be moved against the action of said spring by the fluid under pressure at the inlet end of the valve for opening said perforations and at the same time closing said exhaust port,—and a stop-and-waste cock adapted for shutting off the supply of fluid under pressure from said valve and for relieving the pressure at the inlet end of the valve.

JAY B. RHODES.
